US0D1074202S

(12) **United States Design Patent** (10) **Patent No.:** **US D1,074,202 S**
(45) **Date of Patent:** **** May 13, 2025**

(54) **HANDLE FOR CLEANING BRUSH**

(71) Applicant: **Zhongshan Kamshing Home Electrical Appliance Co., Ltd, Guangdong (CN)**

(72) Inventor: **Minshi Liang, Guangdong (CN)**

(**) Term: **15 Years**

(21) Appl. No.: **29/960,158**

(22) Filed: **Aug. 29, 2024**

(51) **LOC (15) Cl. 04-01**

(52) **U.S. Cl.**

USPC D4/102

(58) **Field of Classification Search**

USPC D4/100, 102, 114, 115, 116, 119, 120, D4/121, 127, 128, 129, 130, 132, 133, D4/134, 135, 136, 138, 199; D32/33, 35, D32/20, 25; D21/795; D24/214

CPC A46B 2200/30; A46B 2200/3033; B08B 1/12

(57) **CLAIM**

The ornamental design for a handle for cleaning brush as shown and described.

DESCRIPTION

FIG. 1 is a front perspective view of a handle for cleaning brush showing my new design;

FIG. 2 is a bottom, rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of an exemplary brush head mounted on the handle of the claimed design; and,

FIG. 10 is a perspective view showing the brush handle with an exemplary brush head mounted on it, with four other exemplary brush heads, all of which are inserted into a brush stand.

The dash-dash broken lines in the drawings depict portions of the handle for cleaning brush that form no part of the claimed design.

1 Claim, 10 Drawing Sheets
